Primary Examiner — Samantha Wood*Assistant Examiner* — Anthony Vincent Rotolo(74) *Attorney, Agent, or Firm* — ALSTON & BIRD LLP(57) **CLAIM**

The ornamental design for an area light as shown and described.

DESCRIPTION

FIG. 1 is a perspective view of an area light according to my new design;

FIG. 2 is another perspective view thereof;

FIG. 3 is a front elevation view thereof;

FIG. 4 is a rear elevation view thereof;

FIG. 5 is a top elevation view thereof;

FIG. 6 is a bottom plan view thereof;

FIG. 7 is a right side elevation view thereof; and,

FIG. 8 is a left side elevation view thereof.

The broken lines in FIGS. 2 and 4 represent portions of the article that are not considered part of the claimed design.

1 Claim, 6 Drawing Sheets(56)
